UNITED STATES PATENT OFFICE.

GEORGE C. STODDARD, OF SOUTH PASADENA, CALIFORNIA.

TOOTHBRAH PROTECTOR.

Application filed November 10, 1924. Serial No. 749,101.

This invention relates to protectors for tooth brushes, said protector being of the type into which the bristle portion of the tooth brush is inserted to protect the bristles 5 against germ-laden dust, and objects of the invention are simplicity and strength of construction.

Another object is to provide a construction that will permit the bristle end of a 10 tooth brush to be thrust upwardly into the receptacle and to provide integral with the receptacle wall a lip or shoulder upon which the lowermost bristles of the brush rest to support the tooth brush that has been thrust 15 into the receptacle, said lip being of a construction that will insure to a large degree against breakage thereof.

A further object is to effect a secure 20 mounting for the receptacle, but one that will admit of ready detachment of the receptacle therefrom so that said receptacle can be easily cleansed.

The accompanying drawings illustrate the invention:

25 Fig. 1 is a side elevation of a tooth brush protector constructed in accordance with the provisions of this invention as the same appears when mounted in position for use, a tooth brush being indicated with the bristle portion thereof inserted in the receptacle.

Fig. 2 is a sectional elevation of the receptacle.

Fig. 3 is a plan section on the line indicated by 3—3, Fig. 1.

35 There is provided a receptacle 4 constructed of any suitable material but preferably of glass, the upper end thereof being closed by a dome-shaped head 5. The receptacle is preferably cylindrical. The lower end of 40 the receptacle 4 is open, as indicated at 6, so that a tooth brush, indicated at *a* in Fig. 1, can be thrust upwardly through the opening 6 in order that the bristle portion of the brush will be covered by the receptacle 4.

45 Interiorally of the receptacle 4 and forming, in this instance, a portion of the wall thereof, is a lip or shoulder 7. This lip or shoulder is formed, in this instance, by the upper portion of a member 8 that is V-shaped in cross section. The member 8 is 50 formed by an indentation in the outer face of the receptacle. The inner edge portion of the member 8 is rounded, as indicated at 9, so that the bristles of the tooth brush will 55 slide past the shoulder 7 without injury to said bristles. The shoulder 7 contracts the

bore of the receptacle 4 sufficiently so that the tooth brush, when inserted into the receptacle with its bristles pointing toward the shoulder 7, cannot pass between the shoulder 60 7 and the opposite side of the receptacle without the bristles being flexed by contact with the shoulder 7. The V-shape of the member 8 is preferably in order that a minimum number of the bristles of the tooth 65 brush will be flexed at any one time while the tooth brush is being inserted in or removed from the receptacle, thus making it very easy to insert and extract the tooth brush.

70 The edge portion 9 of the member 8 forms a chord in the cylindrical bore of the receptacle, both ends of the member 8 being integral portions of the wall of the receptacle, thus providing for a relatively strong 75 lip so that if the lip be struck a hard blow accidentally with the end of the tooth-brush, while inserting the tooth-brush, said lip will not be easily broken.

76 At suitable locations on the outer face of the receptacle 4 are spaced beads 10. In this instance one of the beads 10 constitutes the rim of the receptacle and the other bead is positioned between the lip 7 and rim. The space between the beads 10 constitutes a 80 groove 11 and yieldingly engaging said groove are spring arms having semi-circular portions 12 and outwardly bent tips 13. The spring arms also comprise straight portions 14 which are positioned side by side. The 85 spring arms constitute portions of a bracket constructed, in this instance, from a single piece of strip spring material, the straight portions 14 having projecting therefrom at right angles legs 15 and said legs 15 lie alongside of a straight portion 16 which also lies at a right angle to the portions 14. To remove the receptacle from the bracket, it is only necessary to pull it outwardly from 90 between the tips 13, the curved portions 12 and portions 14 springing apart sufficiently 95 for this purpose. To return the receptacle to the bracket, it is only necessary to force it inwardly between the tips 13.

100 When it is desired to insert a tooth-brush in the receptacle, so that the bristle portion thereof will be protected thereby against germ-laden dust, the operator will insert the tooth-brush endwise into the receptacle, with the bristle portion uppermost, and, when the bristles come into contact with the member 8, he will force the tooth brush upwardly, 105 110

thus slightly flexing the bristles so that the bristle portion will pass the member 8.

After the bristles have passed the member 8 they will spring into their normal straight position and, upon the operator releasing the tooth-brush, the lowermost bristles will catch upon the lip 7 so as to prevent the tooth-brush from dropping out of the receptacle. When it is desired to use the tooth-brush 10 it can be quickly detached from the receptacle by simply pulling it straight downward so as to cause the bristles to be flexed by engagement with the lip 7.

It will be noted that there is no angular 15 portion to the member 8 that the tooth-brush can strike against so as to tend to break said member or to injure the bristles of the brush, consequently there is a decided advantage in having the opposite ends of the member

8 forming integral portions of the wall of 20 the receptacle.

If desired, a hole 17 may be provided in the wall of the receptacle to permit of the escape of watery vapor and to insure air circulation. 25

I claim:

A tooth-brush protector comprising a cylindrical receptacle closed at its upper end and open at its lower end, a member V-shaped in cross section projecting inwardly 30 and the inner edge portion of said member being rounded and said portion forming a chord in the bore of the receptacle, and both ends of said member being integral portions of the wall of the receptacle. 35

Signed at Los Angeles, California, this 27th day of October, 1924.

GEORGE C. STODDARD.
